(57) **CLAIM**

The ornamental design for an archery broadhead, as shown and described.

DESCRIPTION

FIG. 1 is a front right perspective view of a first embodiment of an archery broadhead showing my new design;
FIG. 2 is a front left perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and

FIG. 8 is a bottom view thereof.

FIG. 9 is a front right perspective view of a second embodiment of an archery broadhead showing my new design;
FIG. 10 is a front left perspective view thereof;

FIG. 11 is a right side view thereof;

FIG. 12 is a left side view thereof;

FIG. 13 is a front view thereof;

FIG. 14 is a rear view thereof;

FIG. 15 is a top view thereof; and

FIG. 16 is a bottom view thereof.

FIG. 17 is a front right perspective view of a third embodiment of an archery broadhead showing my new design;
FIG. 18 is a front left perspective view thereof;

FIG. 19 is a right side view thereof;

FIG. 20 is a left side view thereof;

FIG. 21 is a front view thereof;

FIG. 22 is a rear view thereof;

FIG. 23 is a top view thereof; and

FIG. 24 is a bottom view thereof.

The shading lines illustrate portions of the archery broadhead that have a relatively shiny appearance, and the stippling illustrates portions of the archery broadhead that have a relatively dull appearance.

A fourth embodiment of the archery broadhead is a mirror image of the first embodiment.

A fifth embodiment of the archery broadhead is a mirror image of the second embodiment.

A sixth embodiment of the archery broadhead is a mirror image of the third embodiment.

A seventh embodiment of the archery broadhead is the same as the first embodiment, except the stippling is replaced with shading lines.

An eighth embodiment of the archery broadhead is the same as the second embodiment, except the stippling is replaced with shading lines.

A ninth embodiment of the archery broadhead is the same as the third embodiment, except the stippling is replaced with shading lines.

(Continued)

A tenth embodiment of the archery broadhead is a mirror image of the seventh embodiment.

An eleventh embodiment of the archery broadhead is a mirror image of the eighth embodiment.

A twelfth embodiment of the archery broadhead is a mirror image of the ninth embodiment.

Portions of the archery broadhead shown as broken lines form no part of the claimed design.
